UNITED STATES PATENT OFFICE.

RANALD T. McDONALD AND JACOB CAIN, OF FORT WAYNE, INDIANA, ASSIGNEES TO THE FORT WAYNE ELECTRIC LIGHT COMPANY, OF SAME PLACE.

ELECTRIC-ARC-LAMP HEAD-LIGHT.

SPECIFICATION forming part of Letters Patent No. 415,252, dated November 19, 1889.

Application filed August 14, 1885. Renewed May 6, 1889. Serial No. 309,801. (No model.)

To all whom it may concern:

Be it known that we, RANALD T. McDONALD and JACOB CAIN, citizens of the United States, residing at Fort Wayne, in the county 5 of Allen, in the State of Indiana, have jointly invented certain new and useful Improvements in Electric-Arc-Lamp Head-Lights; and we do hereby declare that the following is a full, clear, and exact description of the invention, 10 which will enable others skilled in the art to which it appertains to make and use the same, reference being had to the accompanying drawings, which form part of this specification.

15 Our invention is of an improved adjustable electric-arc-lamp head-light.

In the drawings, Figure 1 is a front view of the head-light. Fig. 2 is a side view of the same. Fig. 3 is a detail of the lamp-connections, and Fig. 4 is a detail of the windlass.

Identical parts are denoted by the same letters in all the figures.

R is the reflector.

At C and C' are holes, through which the 25 carbons enter from above and below. Two sleeves S and S', rigidly connected with the reflector, slide up and down on two standards s and s'. A cable A' A' A' is attached to the arm-connections of these sleeves and carried 30 under the pulley p⁵ and over the pulleys p⁶, p⁷, and p⁸. A block on pulley p⁵ is made fast to another cable, which passes by the pulleys p⁴, p³, p², and p' to one section of the windlass W, by turning which the reflector 35 R is raised or lowered to adjust its focus to the voltaic arc between the carbons. The cable H H H H has a turn around the drum D at the base of the head-light and another around the other section of the windlass W, 40 by means of which the head-light is turned upon its hollow central axis.

At l is a supporting-cable which limits the drop of the reflector R.

At Fig. 3 is shown the wooden cross-piece 45 which supports the wire connections of the lamp. B is the central aperture below the hollow axis, through which the cable A passes from p³ to p³.

At sp and sp' are two brass springs electrically connected with the binding-posts w

and w', respectively, and which press upon two corresponding circular brass tracks on the under side of the drum D, insulated from each other, and through which the connections of the lamp are made.

55

At sw is a switch by which the lamp-circuit may be opened or closed.

The regulating mechanism of the lamp is in L.

The windlass W has two separate axles— 60 one for the cable A A A, the other for the cable H H H H. Each axle has a wheel and radial arms, and the axle carrying the drum-cable H H H H has also a crank c, which has a divisible arm, as shown at the sections c' 65 and c² in Fig. 4, which may be adjusted in length by bolts through the holes shown in the crank in Fig. 1.

The form of construction here shown is designed specially for use on a steamboat. To 70 one familiar with the art modifications of it embracing the principles of our invention and adapting it to other uses will readily suggest themselves.

We are aware that electric head-lights for 75 locomotives have been patented with a capacity for vertical adjustment to properly regulate the focus, and for a lateral adjustment, both produced by means and connection which are rigid throughout, and such inventions we disclaim, as they would be unsuitable for head-lights for vessels, particularly steamboats, where a radial adjustment of the head-light is essential, particularly at landings and where the means for producing 80 the several adjustments must be flexible.

85 We claim as our invention—

An arc-lamp head-light consisting of a main casing, a reflector R within the same and mounted on the standards s s', the cable A 90 A', passing over the pulleys p p⁸, for raising and lowering the said reflector and secured to one portion of the sectional windlass W, the carbons C, extending through openings in said reflector for the purpose mentioned, a 95 drum D at the lower portion of the main casing, a continuous cable around said drum and extending to the other portion of said sectional windlass, by means of which the main casing may be partially revolved, so that 100

the light may be thrown in the path of a circle, the two spring-contacts sp sp' , connected with the binding-posts w w' , respectively, and bearing against the tracks on the bottom 5 of the drum D, and a switch sw , interposed in the circuit, by which the circuit may be opened or closed, substantially as set forth.

In testimony whereof we hereto subscribe

our names, in the presence of two witnesses, this 12th day of August, 1885.

RANALD T. McDONALD.
JACOB CAIN.
